BOTTLE CAPPING MACHINE

Lewis E. Fagan, Chicago, and Albert B. Mojonnier,
Park Ridge, Ill., assignors to Mojonnier Bros.
Co., a corporation of Illinois

Application June 7, 1937, Serial No. 146,809

10 Claims. (Cl. 226—92)

The present invention relates to bottle capping machines, and more particularly to machines of this class which apply closing disks to milk bottles, although in some instances the novel features may have a broader application than this. However, since the invention was conceived and developed in connection with the capping of milk bottles, the same will be illustrated and described in that connection.

10 The present invention is an improvement upon the capper construction disclosed in our prior United States Patent Number 1,992,693, granted February 26, 1935.

15 In capping machines of the kind in view, a rock shaft carries a cap advancing blade which delivers the caps one by one from a stack into a capping position where they are applied to the bottles. The shaft is rocked through the agency of a rocker arm and a cam. Spring means serve to 20 restore the shaft to its initial position.

25 One object of the present invention is to provide actuating mechanism of this kind wherein friction among the several parts will be avoided as much as possible. More particularly it is desired (1) to reduce the engagements of the rocker arm with its operating cam to a minimum, (2) to avoid all sliding engagements of the rocker arm cam wheel upon the surface of the operating cam, and (3) to remove all ram body friction 30 due to spring pressure.

35 To this end we employ novel catch mechanism which seizes the rocker arm in an outer position and holds it there out of engagement with the cam during certain periods of travel and especially at times when the rocker arm receives vertical movements, as it does when the machine is in operation. The cam periodically brings the rocker arm to its extreme position and there it is seized and held beyond the control of the cam until the 40 time of its release arrives, whereupon it comes again under the control of the cam.

45 Another object is to provide a suitable spring arrangement for the rock shaft which will enable the cap advancing blade to stop always in a certain position and still allow the rocker arm to advance far enough to properly cooperate with the latch mechanism without shifting the blade. This is very important since the blade point and two other points or projections on the capper 50 frame provide a three-point support for the caps in the cap magazine.

55 Another object is to provide the cap-engaging end of the cap advancing blade with a novel construction such that the blade will handle and properly advance any one of a number of differ-

ent caps, such as plain disks, single and double tabbed caps, caps having tabs secured thereto by wire staples, and the like.

Another object is to provide a novel ram structure so that the various caps may be properly applied and at the same time a standard basic construction may be adopted which will require but slight alteration to suit the ram to caps of different kinds and sizes.

The novel features and advantages of the invention will be more fully understood upon reference to the following detailed description taken in connection with the accompanying drawings and the scope of the invention will be particularly pointed out in the appended claims.

In said drawings, Fig. 1 is a central vertical section through the upper portion of a bottle capping machine constructed and arranged in accordance with the present invention, the section being indicated by the line 1—1 of Fig. 3; Fig. 2 is a similar vertical section through the lower portion of the machine, the section being indicated by the line 2—2 of Fig. 4; Fig. 3 is a plan view of the upper portion of the machine showing particularly the actuating cam and various capper elements associated with it, the point of bottle feed and delivery being indicated diagrammatically by the associated wheels and guides at the left of the figure; Fig. 4 is a horizontal section taken on a plane indicated by the line 4—4 of Fig. 2; Fig. 5 is a vertical section through one of the vertically movable capper frames and associated parts, showing clearly the cap magazine and the ram, the plane of section being indicated by the line 5—5 of Fig. 6; Fig. 6 is a horizontal sectional view through the same capper frame and associated parts, the plane of section being indicated by the line 6—6 of Fig. 5; Fig. 7 is a plan view of the lower portion of one of the vertically movable capper frames in association with the cap actuating blade assigned to 35

that frame in its withdrawn or back position, the view being along the plane of separation between the lower frame members and indicated by the line and associated arrows 7—7 of Fig. 5; Fig. 8 is a perspective view of a cap actuating blade member; Fig. 9 is a bottom plan view of that portion of the previously illustrated capper frame which lies above the separating line previously mentioned and the direction of view is that indicated by the line and associated arrows 9—9 of Fig. 5; Fig. 10 is a sectional view of the cap-engaging end of the cap applying blade, the section being vertical and on a plane indicated by the line 10—10 of Fig. 7; Fig. 11 is an elevation 40

45

55

of a cap-applying mechanism associated with one arm of the supporting head, said arm being shown in section taken on a plane indicated by the line 11—11 of Fig. 1; Figs. 12 and 13 are perspective views of cooperating members forming part of the catch mechanism; Figs. 14 to 19 inclusive illustrate the capper parts, and especially the parts of the catch mechanism, in various operating positions, Fig. 14 showing the same at the time, shortly following the delivery of a bottle to the associated lifter, when the rocker arm is nearing its extreme position wherein it is about to be seized and held by the catch mechanism, the latch pin passing upward by reason of engagement with the inclined face of the associated stop, Fig. 15 showing the parts with the catch pin advanced beyond the stop and down behind the same, the actuating cam and cam roller still being in engagement, Fig. 16 showing the parts just a little farther advanced, the catch pin having moved into engagement with the abrupt square face of the stop and the cam roller having cleared the cam face, Fig. 17 showing the parts still later with the cam and cam roller clearance increased and the auxiliary stop dropped down into blocking position beneath the catch pin, the vertically movable capper frame having been raised by the lifter acting through the carried bottle at first by the application of low pressure air and then later by the application of high pressure air, the cam roller meanwhile remaining clear of the cam, Fig. 18 showing the parts just as the catch pin being blocked by the auxiliary stop is about to pass the end of the beveled stop, the cam roller and cam still remaining clear of each other, and the cam roller having descended to its low position in consequence of the descent of the vertically movable capper frame, and Fig. 19 showing the parts after the rocker arm is freed from the catch mechanism and is again under the control of the cam; Fig. 20 is a perspective view of the catch mechanism members of Figs. 12 and 13 in assembled relation; and Fig. 21 is a cross-section of the central column, the plane of section being taken on a plane indicated by the line 21—21 of Fig. 1. Throughout these views like characters refer to like parts.

It may be pointed out at the beginning that the bottle capper disclosed in the drawings consists essentially of a base A, an upright column or standard B, a rotary bottle carrier C journaled to rotate about said column as a center, a series of pneumatically actuated bottle lifters D positioned upon the carrier, a rotary supporting head E near the top of the column, a series of vertically movable bottle centering frames F carried by the supporting head E and aligned with the lifters D respectively, cap actuating mechanism G associated with each capper frame F, a central cam H near the top of the column cooperating with the actuating mechanism G and adjusting mechanism K located beneath the base A and operating to shift the various parts at the top of the column B.

The essential features of the invention reside in and about the vertically movable capper frames F, the cam H and the cooperating actuating mechanism G. Here are found the novel catch mechanism, the novel return spring arrangement, the specially shaped cap advancing blade point, the three-point suspension for the caps in the cap magazine, the novel ram construction, and other features with which the invention is more particularly concerned.

In operation, the bottles are fed one by one

upon the lifters D as the latter present themselves at a common feed point. The carrier C which supports the bottle lifters D is directly connected to the supporting head E and the latter directly supports the capper heads F. Consequently as the carrier rotates all these parts rotate with it. During the travel of these parts, the bottles are successively raised and lowered. When raised they raise the vertically movable capper frames F and the caps are applied. Following the capping operations the bottle lifters are successively lowered and brought to a delivery point where the capped bottles are discharged from the machine.

In case a particular lifter is not supplied with a bottle when it reaches the feed point, then there is no upward movement of the associated capper frame and the result is that the feeding mechanism G remains latched and held out of action until the carrier has made another revolution. Upon the completion of such revolution, if now a bottle is present upon the associated lifter, then the bottle will lift the head and the operation will be regular as just indicated.

Having pointed out the essential parts of the machine and its general operation, attention may be directed to the details of the several parts.

The base A includes a pedestal 25 mounted upon a flat plate-like support 26 which forms part of the frame of the machine, other portions 30 of the frame including the upright flanges 27, 28 and a table 29. In the embodiment of the invention which has been put into service the frame parts just mentioned are parts of a large frame which supports the capper and in conjunction with it, a filler. The latter, however, is not part of the present invention and is therefore not illustrated.

The pedestal 25 has a peripheral flange 30 and securing bolts 31 pass through this flange and on down through openings in the frame plate 26. Nuts 32 serve to securely hold the parts together. The openings in the plate 26 through which the bolts 31 pass are large enough to allow of some relative movement between the pedestal 25 and the plate 26 so that the former may be properly centered with reference to other parts carried by the frame of the machine. For the purpose of providing these adjustments, a plurality of sets of screws 33 are employed. The screws of the illustrated set extend through threaded openings in the flanges 27 and 28 respectively and operatively engage opposite sides of the flange 30. By letting off on one or other of the pair of adjusting screws 33 and tightening up its companion it is possible to shift the pedestal 25 in any desired direction upon the plate 26, within the limits of the openings through which the bolts 31 pass. It will be apparent that ordinarily there will be at least two pairs of adjusting screws 33 and associated parts in order to give a proper centering of the pedestal 25 upon the plate 26, although but one such pair is illustrated. When the pedestal 25 is properly positioned upon the plate 26, then the nuts 32 may be screwed up tight upon the bolts 31 and thus the base parts will be securely held in place. The center of the base pedestal 25 is bored out or otherwise provided with a central opening for receiving the parts of the vertical column B.

The column B includes a stationary tubular standard 34 which is fitted in the vertical bore in the pedestal 25 and secured therein in any suitable way as by a feather 35 held in place by a set screw 36. At its lower end the standard 34

has a bearing ring 37 which is secured to the standard and serves as a bearing for the adjusting rod 38 which extends upward through the standard 34 and carries the supporting head E and other parts in a way which will be presently pointed out. A similar bearing ring 40 is located at the top of the rod 38. The rod 38 is free to reciprocate in the tube 34 but is held against rotation by a plurality of feathers 39 carried by the rod, being held in each instance by screws 41, and operating in suitable slots in the bearing ring 40 which is secured to the inside of the tubular standard 34. These bearing rings 37 and 40 are preferably given a press fit in the standard.

The upper end of the tube 34 is also provided with an outer bearing ring 42. This ring is similarly firmly secured to the fixed tube 34 and serves as a bearing for the rotary tubular member 43 which connects the supporting head E and the rotating base or carrier C so that the two rotate together, although connection is provided by which the head E may be raised and lowered with reference to the standard 34 and the connecting tube 43. The carrier C is a round casting provided near its periphery with a series of spaced posts 44 which carry the parts of the lifters D. The body 45 of the carrier is centrally apertured so as to pass freely over the standard 34 of the column B. The central bore of the carrier also has a bearing ring 46 which has a close fit with the body 45 and rotates with the carrier C about the standard 34. The central bore of the carrier C is also slightly increased in diameter at its upper end so as to receive the lower end of the tubular member 43. A key 47 between the flange 48 of the carrier and the tube 43 serves to hold the parts together against relative rotation. The key 47 is in turn held in place by a set screw 49. The carrier C has a peripheral flange or petticoat 50 which overlaps an upturned flange 51 on plate 29 and the upper end of the upright flange 27 of the base.

The posts 44 of the carrier are provided with passages 52 for supplying compressed air to the lifters and exhausting the same therefrom. The passages 52 communicate with inclined passages 53 in the body 45 of the carrier and these inclined passages in turn communicate with vertical passages or ports 54 which terminate at the under annular bearing surface of the carrier. This surface rests upon a bearing ring 55 which is supported by the base pedestal 25 at a single bearing point furnished by the upper end of the supporting pin 56. This pin enters a vertical opening in the base A and may be adjusted up and down by a vertical adjusting screw 57 which is threaded through a threaded opening in the base A and thus forms a bearing or support for the lower end of the pin 56. This pin is the sole support for the bearing ring 55 and the movable base or carrier C supported by it. The screw bolt 57 is locked in position by a lock nut 58.

The under bearing surface of the carrier, in which surface the ports 54 terminate, and the upper bearing surface on the upper side of the bearing ring 55, are in effect the valve faces of a distributing valve which controls the air supplied to and exhausted from the several lifters D.

The one point support for the bearing member 55 and the parts supported by it, is most effective in maintaining good contact between these valve faces at all times. To insure such good contact, the pipes by which the compressed air is supplied, namely pipes 60 and 61, are connected at

their lower ends to pieces of hose 62 and 63 respectively. The upper ends of the pipes are firmly screwed into openings in projections 64, 65 extending outward from the bearing ring 55. Such connections may be made directly or through a union and nipple as shown in the case of pipe 61 in Fig. 2. By this construction it is obvious that the pipes 60, 61 will rise and fall with the bearing ring 55, all relative motion being taken up by the hose connections. Thus, there is a continued maintenance of the requisite close engagement between the bearing surfaces on the carrier C and the ring 55.

It is by means of the pin 56 that the height of the carrier C, and hence the height of the lifters D, is varied. This variation in height enables the machine to be properly adjusted relative to the conveyors which bring bottles to the machine and carry them away from it.

The upper bearing surface of the bearing ring 55, which may be designated generally 66, is provided with an annular groove which is divided by plugs 67, 68 and 69, into three operating segments having ports 70, 71 and 72. The port 70 is at the end of a passage 73 which leads to the low pressure pipe connection 60, 62. In like manner, port 71 is associated with a passage 74 which is in communication with the high pressure air supply pipe connection 61, 63. The third port 72 is similarly associated with a passage or outlet 75 which leads through the wall of the bearing member 55 to atmosphere.

In putting the invention into practice, we have used for our low pressure air a pressure of from eight to ten pounds per square inch. For the high pressure air, we have used a pressure varying from about fifteen pounds to twenty-five pounds per square inch. The low pressure is sufficient to bring the copper head and bottle together, and the high pressure is used to bring about a complete setting of the cap against the shoulder in the neck of the bottle. These operations are the same as fully explained in our aforesaid Patent No. 1,992,693 and need not be particularly explained.

A circular toothed ring gear 76 is secured to the under side of the carrier C by machine screws 77 or other suitable means, and this gear is driven through the agency of a cooperating gear wheel 78 upon a vertical shaft 79 suitably journaled in an adjacent portion of the frame plate 29. The rotation of the carrier is continuous as long as the wheel 78 is in operation, the main bearing of the carrier being the bearing ring 55 previously mentioned. The latter is relatively fixed and responds only to forces which tend to improve its engagement with the bearing face of the carrier.

In this connection, it should be noted that the under face of the member 55 is provided with a radial groove 80 and the head at the upper end of the bearing pin 56 is cut away to provide a feather 81 on its upper face. This feather 81 is of sufficient size to fit snugly in the groove 80. The groove enables the member 55 to be moved more or less without dislodging or placing any particular strain on the pin 56. On the other hand, the feather 81 on the end of the pin 56, by engaging in the groove 80, holds the bearing member 55 against any possible rotation.

The pneumatically actuated lifters D, as previously pointed out, are spaced around the periphery of the carrier C and include the upstanding posts 44. In the interior construction they are like the lifters disclosed in our prior Patent No. 1,966,889, granted July 17, 1934. However, we have

fully illustrated said construction and the same may now be described.

- Each lifter D includes in addition to its post 44, also a head 82 having a skirt or cylindrical wall 83 which passes down around the post 44. The connected head 82 and skirt 83 form an open ended cylinder and by providing an air-tight, or substantially air-tight, sliding connection between the skirt 83 and the top of the post 44, it is possible to elevate the cylinder by admitting compressed air into the space beneath the head 82. The passage through which air is thus admitted is, in the case of each lifter D, the passage 52 previously mentioned.
- 15 The substantially air-tight connection between the cylinder wall and the top of the post is provided by a cup packing 84 which is secured between retaining rings 85 and 86 by machine screws 87 which pass down through the parts into threaded openings in the top of the post 44. The packing 84 is upturned and fits snugly against the interior surface of the cylinder wall 83. The packing 84 is preferably a synthetic rubber packing having good wearing properties.
- 20 From what has been said, it will be seen that the cylinder may be easily elevated by the admission of air through the passage 52. Now, in order to return the cylinder to its lowermost position and thus clear out the cylinder when an exhaust 25 position is reached, we employ a return spring and dash pot construction. To this end, the head 82 is connected to the upper end of a rod 88. This rod is seated in a recess formed within an annular flange 89 extending downward from the head 82. A pin 90 connects the piston rod 88 to the head 82, the connection being made by passing the pin through the flange 89 and a small transverse hole drilled through the upper end of the rod. The rod 88 is held against rotation by means of two keys 91 which extend into longitudinal slots 92 cut in opposite sides of the rod. The keys 91 are secured to the upper end of a tube 93 and the latter is suitably secured to the post 44. Thus the head is held against rotation but is allowed to move up and down. The upper end of the tube 93 has a thickened annular portion 94 which is notched to receive the keys 91 and the latter are firmly secured in place by rivets 95 or like suitable retaining means.
- 30 The tube 93 extends down into a central well 96 formed in the post 44. It is preferably secured in place by a pivot point set screw 97 which is threaded through a threaded opening in the post 44 and passes at its inner end into a hole in the wall of the tube 93. The screw 97 is preferably provided with a cap nut 98. Between the cap nut 98 and wall of the post 44 is a gasket 97a which being set into a recess in the face of the post has a tight fit with the same and so prevents leakage of air. The downward pull upon the head 82 is furnished by a coiled compression spring 99 which bears at its upper end against the under side of the overhanging thickened portion 94 of the tube 93 and at its lower end upon the upper side of a dash pot piston 100 which is secured to the lower end of the rod 88. The piston 100 may fit loosely in the well 96 and perform its proper dash pot functions. When in service, the well 96 is filled with oil or other retarding liquid 45 to a suitable level. The expansive force of the spring 99 is such that when actuating compressed air is removed from the cylindrical space below the head 82, then the spring will bring the parts downward and leave the head in substantial engagement with the top of the post 44. Each head

82 is preferably provided with a wear plate 101 suitably secured in place.

The rotary supporting head E, as previously pointed out, is secured to the connecting tube 43 so as to rotate with the carrier C. On the other hand, it is mounted so as to slide up and down with reference to the connecting sleeve 43, this up and down movement being brought about by raising and lowering the adjusting rod 38. The connection between the head E and the tube 43 is provided by locating a plurality of longitudinal slots 102 on the inside of the hub 103 and using with them a like member of feathers or keys 104 secured to the tube 43 by suitable means such as the screws 105.

15 The connection between the supporting head E and the adjusting rod 38 includes a sleeve 106 which is flanged at its lower end and such flange secured to the top of the head E by machine screws 107 or other suitable means. The sleeve 106 has an apertured head 108 at its upper end and the rod 38 extends through the aperture in this head. A cooperating coupling member 109 takes the form of a stout ring apertured to fit the rod 38. The latter is reduced a little in diameter and thus a shoulder is provided against which the lower inner edge of the member 109 abuts and thus the member is supported. Above the member 109 is an end member 111 which comprises a sleeve 112, a flange 113 and an outer skirt 115. The sleeve 112 embraces the rod 38 and the sleeve 115 fits over and encloses the upper end of the sleeve 106 secured to the head E. Nuts 116 threaded upon the upper end of the rod 38, which is threaded for the purpose, press the members 109 and 111 firmly down into clamping position on opposite sides of the apertured head 108 associated with the sleeve 106. A suitable key 117 in keyways in the rod 38 and member 111 hold the parts against rotary displacement relative to each other. Thus the cam carrying parts are secured against rotary movement while being free for vertical adjustment. On the other hand the tube 43 which connects the carrier C and the head E is free to rotate by reason of the head 108 being free to rotate. The latter is separated from adjacent parts by washers 118 but there is no pressure in the assembly which interferes with the rotation mentioned.

50 The cam H is provided by a downwardly extending flange 121 positioned at the periphery of a substantially horizontal plate 122 of the heart shaped outline shown in Fig. 3. The outer surface of the flange 121 constitutes the cam face which the cam rollers of the several actuating mechanisms G engage in the operation of the machine.

The supporting head E is provided with a number of arms 123 which terminate at their outer ends in bosses 124 which are provided with vertical openings into which the stems 125 of associated cap applying rams 126 are adapted to extend. By giving the upper end of each ram a taper and fitting the same into a tapered hole in the associated arm 123 and employing a nut 127 on the threaded upper end of the ram stem, together with an associated washer 128, the ram may be firmly secured to the arm. In order to position the ram accurately with reference to the arm, the two should be fixed against rotation when assembled. To this end the wall of the opening in which the stem 125 fits is provided with a slot 129. Cooperating with this slot is a key 130 secured to the stem 125. The key 130

comprises an outer portion 130^a which cooperates with the slot 129. It also comprises a base 130^b which is seated in an arcuate pocket formed in the stem 125. A screw 130^c passes through the key 130 into threaded engagement with the stem 125 and thus holds the key in place.

The plunger or ram 126 in each instance carries the vertically movable capper frame F. This frame or head includes an upper casing 131 and a lower bottle centering member 132. These two parts are connected together in any suitable way as by means of the machine screws 133. The frame F is held in place upon the ram 126 by a transverse pin 134 which is passed through a slot 135 in the frame member 131 into an opening in the ram. The pin is removable and by removing it from the ram when the frame is in its uppermost position it will be easy to withdraw the frame from the ram also. The movement of the frame will bring the pin into the lower end of the slot. When the parts are thus positioned the pin may be readily removed. The separation of the parts in the way indicated will enable them to be readily and thoroughly cleaned. While the pin is in the slot the frame may be moved up and down on the ram within the limits of the slot.

The member 131 includes not only the cylindrical passage 137 in which the ram 126 is adapted to move, but it also includes a cap magazine 138 in which the caps 139 are stacked. As clearly shown, the stack of caps 139 occupies a position parallel to that occupied by the piston 126.

The lower frame member 132 is recessed on its under side so as to provide a sort of pocket 140 into which the upper end of the bottle will fit snugly. A further opening 141 through the member 132 provides a passage for the ram in its downward travel. The upper portion of this opening 141 is beveled slightly as indicated at 142 and thus provides a throat for the cap being applied. Thus, when the capper frame F is moved upward by the associated lifter, when a bottle is properly positioned, then the slightly converging wall 142 will cause the cap, such as the cap 143 of Fig. 5, to be moved down through the opening 141 with the result that the cap will be contracted in diameter and when it passes into the top of the bottle and is pressed home upon the shoulder thereof, it will spring outward into firm and tight engagement with the interior of the bottle neck above the shoulder and thus form a tight seal.

Now, when it comes to positioning the caps one by one beneath the associated plunger, we make use of the cap actuating blade member 144. This blade member is an important element of the cap actuating mechanism G, previously mentioned. The blade member includes an arm 145 which extends outward from a boss 146 and at its outer end it carries the cap engaging blade 147 which has a somewhat extended arcuate upper surface so that it may underlie the stack of caps when in its most advanced position and hold them thus elevated until it has passed on its return stroke far enough to allow them to fall in position so that it will upon its next advance engage only the edge of the lowermost cap to advance it, while leaving the others intact in the cap magazine. This action will be better understood when it is realized that the member 132 is provided on its upper surface with a depression 148 which is arcuate and extends between the magazine chamber 138 and the capper chamber 137. It is in the pasageway formed in part by

this depression 148 that the blade 147 travels in its to and fro oscillations. The channel for the blade is not formed wholly by the depression 148 in the member 132 but part of it is formed by a cooperating depression 149 formed in the member 131. These arcuate depressions are clearly shown in Figs. 7 and 9, and from them it will be understood that when the members 131 and 132 are properly assembled, there will be a proper resulting channel for the movements of the cap actuating blade 147.

It will be apparent that when the forward edge of the cap engaging blade 147 has passed to the left of the cap magazine 138, as the parts are viewed in Figs. 6 and 7, then the entire stack 15 of caps will rest upon overhanging frame portions 150 and 151 of the member 132 and upon the point of the blade 147, the three supports thus provided constituting a three-point support for the lowermost cap of the stack, and consequently of the stack. This three-point feature is shown most clearly perhaps in Fig. 7.

These projections 150 and 151 and the point of the blade 147 constitute the sole support of the caps when the blade 147 is in its left-most position, as the parts are viewed in Figs. 6 and 7. With the parts in this position, the lowermost cap, as, say, the cap 152 of Fig. 10, will rest upon the ledges 153 and against the shoulders 154 formed adjacent thereto in readiness to be advanced by the next forward movement of the blade 147. Just back of the shoulders 154 are the inclined planes 155. The purpose of these beveled or inclined surfaces is to cause the caps to separate just as in our prior Patent No. 3,199,693. By inspecting Fig. 10 it will be seen that as the blade 147 moves toward the right under the stack of caps, the lowermost cap 152 will be advanced while the ones above it will be held by the walls of the magazine 138. As a result the cap just above the cap 152 will slide up over the bevels 155 and separate from the cap 152, leaving the latter free to advance while the remaining caps are separated from it and left behind in the magazine.

As the blade still further advances, this forward edge will push the cap along the channel formed by the mating depressions 148 and 149, while the upper surface of the blade 147 will ride freely under the next cap of the stack, that is to say, the cap immediately above the one being advanced by the blade. In this way, the upper face of the blade holds the stack elevated and maintains it in this condition all through the advance travel of the blade and then until the blade has entirely receded to its starting point beyond the cap magazine. The withdrawal of the blade 147 will then allow the stack column to descend upon the ledges 153 and remain there in readiness for the next like operation.

While considering the operation of the blade 147 in advancing a cap, it should be noted that what has been said will apply equally well to a plane disk cap, a single tabbed cap or a double tabbed cap, and that whether the tabs be stapled or made integral with the body of the cap. In Fig. 10, the caps, illustrated in dotted lines, are simple disk caps but tabbed caps may be utilized as well. As shown particularly in Fig. 6, the magazine 138 is shaped so as to take in plain disks or single or double tabbed caps. The point of the blade 147 is also still further specially shaped and this is done principally to better take care of the tabs on the caps and the possible protrusion of the wires forming the staples where

such are employed. Thus, the space or recess 156 at the rear of and extending between the ledges 153 and the shoulders 154 is provided to receive cap tabs. Similarly, the inclined face 157 just forward of the ledges 153 serves to guide the wires of the staples upward. In other words, the incline 157 slides freely under the wires of the caps and greatly improves the action of the blade or flipper 147. Without the bevel 157 there is greater danger of the blade engaging the wire of a wire-stitched cap and thereupon feeding it too far or in some other improper way.

Now, in order to give the blade 147 its proper movements back and forth in the channel between the cap magazine and the ram chamber, we provide a rock shaft 160 and journal the same in bearings formed in lateral extensions 161 and 162 forming part of the vertically movable cap-frame F. The lower end of the shaft 160 receives the boss 146 of the blade member 147 and the two are firmly secured together by any suitable means as by the pin 163. The upper portion of the shaft 160 has the rocker arm 164 journaled upon it. The inner end of the arm is divided into two bearing arms 165 and 166 which provide two journals for the supporting rock shaft 160. Thus, the rocker arm is journaled on the rock shaft 160 and the rock shaft in turn is journaled upon the cap-frame F. The boss 146 of the blade member by acting against the member 162 holds the rock shaft against upward displacement relative to the frame F and a castellated nut 167 and associated cotter pin 168 just above the bearing arm 147 serve a like purpose relative to downward displacement of the rock shaft.

The requisite rocking movements are brought about by spring pressures and oscillations of the rocker arm.

The crank arm 164 terminates at its outer end in a vertically disposed sleeve 171. The upper end of the sleeve opening 172 is closed by a bearing pin 173 which is fixed in place in the sleeve by a set screw 174 or other suitable means. On the bearing pin 173 is journaled an anti-friction roller 175. This roller is held in place by a suitable nut 176 which is threaded upon the upper end of the bearing pin 173 and held in place by a cotter pin 177. It is the anti-friction roller 175 which engages the cam face on the flange 121 of the cam member H. The sleeve 171 also carries a catch pin 178 which is passed through an opening at the lower end of the sleeve chamber 172 and is limited in its downward movement by a collar 179 which engages the floor of the chamber 172. A coiled spring 180 acts between the under side of the bearing pin 173 and the upper side of the catch pin 178. In order to center the spring 180, these pins are respectively provided with reduced ends which pass into the coiled ends of the spring.

We also employ upon the rock shaft 160 two coiled springs 181 and 182. These are torsion springs and cooperate with the rocker arm 164 and the cap advancing blade 147. The blade is moved to its advanced position by the spring 182 and to its rearmost position by the rocker arm 164 acting against this spring. The spring 181 is in a sense supplemental to the spring 182 and comes into play only to bring about a proper operation of the rocker arm without interfering with the proper operation of the cap advancing blade.

When the blade member 147 reaches its foremost position, a stop 183 on the under side of

the blade engages with a portion 184 of the frame member 132 to limit the forward movement of the blade. The opposite movement of the blade is limited by the engagement of a stop projection 185 on the blade coming into contact with a stop projection 186 on the frame member 132.

The springs 181 and 182 are coiled about the shaft 160 and are arranged so as to be given more or less tension. In the case of the spring 181 the lower end 187 is turned downward and passes into an opening in the bearing arm 166 of the crank 164. The opposite end of the spring 181 is provided with an upturned end 188 which passes into a vertical opening in an adjustable collar 189 which rides upon the shaft 160. A pin 190 cooperates with holes 191 in the collar 189 and with a single hole through the shaft 160 to bring about adjustments of the spring. It will be obvious that when the spring is wound up and the pin 190 is inserted into the shaft through the appropriate collar opening 191, the spring will be held under tension and there will be a spring action between the rocker arm 164 and the shaft 160. The several holes 191 permit of a number of adjustments.

When it comes to the spring 182, a similar arrangement is provided. In this instance the upper end of the spring 182 is provided with an upturned end 193 which enters a suitable opening 194 in the under side of the projection 161 of the frame F. Similarly the end 194 of the spring 182 enters an opening in the collar 192. Just as before, the collar is provided with a series of openings 195 which are intended to cooperate with a transverse opening through the shaft 160. A pin 196 is used in securing the collar 192 to the shaft after the spring 182 has been wound up so as to give it proper tension. Any desired adjustment may be had.

As stated the blade member normally rests in advanced position with the stop members 183 and 184 in engagement. It is the spring 182 which brings about this normal positioning of the blade. Since the rock shaft is fixedly secured to the blade member it will be obvious that the latter is only yieldingly held in its advanced position with the stops 183 and 184 in engagement. This positioning of the blade is brought about wholly by the spring 182. The spring 182 is weaker than the spring 181 and consequently that pressure upon the rocker arm 164 which is necessary to rock the shaft will not tend to move spring 181 with reference to the shaft but will instead move the shaft with reference to the frame F, thereby placing the spring 182 under greater tension. It is the action of the rocker arm 164 under the control of the cam which moves the blade from its normal yielding position, just described, to its back position wherein the stops 185 and 186 engage each other.

Now in the operation of the blade and the rocker arm it is necessary for the rocker arm to pass through a greater arc than the blade. In other words, after the rocker arm has moved the rock shaft so as to bring the stops 185 and 186 into engagement then the rocker arm must be free to move a short distance further in order that it may properly be engaged by the catch mechanism without disturbing the position of the blade. It is at the time when this additional movement is given to the rocker arm that the spring 181, the stronger spring of the two, comes into play.

Thus, it will be clear that on the rearward

movement of the blade, the rocker arm places increased tension in the springs 182 and 181 in succession. While tension is being added to spring 182 the blade 147 is traveling rearward. As soon as it is stopped, the rocker arm begins to act upon the spring 181 and places tension in it, which tension serves to bring about proper action with the catch mechanism as we shall see presently.

10 Before passing from our consideration of the actuating mechanisms G, it will be necessary to consider the catch mechanism. There is one such mechanism for each rocker arm. These mechanisms are brought into play when the arms 15 are moved severally to their advanced positions. Each catch mechanism seizes the associated arm and holds it in its extreme position and thus frees the cam roller 175 from engagement with the cam face at those times when the capper 20 frame F is moved vertically in the operations of capping the bottle.

The elements of the catch mechanism are secured, respectively, to the vertically movable capper frame F and to a fixed member, which does 25 not move with this frame. In the embodiment illustrated, each arm 123 is provided with an extension 199. To this extension is pivoted an irregularly shaped stop member 200 which cooperates with a main stop member 201 fixedly 30 secured to the frame F. Thus, the main stop member 201 and the supplemental stop member 200 are secured to supports which move relatively to each other. The main stop member 201 has a cylindrical shank 202 at its lower end which 35 enters an opening in a projection 203 extending from the frame F near its upper end. A set screw 204 secures the member 201 in fixed position upon the frame member 131. The projection 199 is in substantial vertical alignment with the projection 203 and consequently the two members 200 and 201 are brought into intimate relation with each other and at proper times with the catch pin 178 carried by the rocker arm 164. The parts are related as illustrated in Fig. 20. The main stop 40 member 201 has a main body 205 and a laterally extending blade 206. The upper ends of the body 205 and blade 206 are beveled as indicated at 207.

It will be noted that both the main stop 201 and the rocker arm 164 which carries the catch pin 178 are carried by the same part, viz., the vertically 50 movable capper F and therefore move together. The rocker arm, of course, has an additional lateral movement and it will be clear from an inspection of Figs. 14 and 15 that, as the rocker arm is moved toward the left, as the parts are shown in those figures, the end of the catch pin 178 will contact the inclined face 207 of the main stop 205, and, as the arm advances, the pin will be forced into the sleeve 171 against the 55 pressure of the spring 180. It will also be observed that when the pin 178 has cleared the end of the inclined surface 207 it will no longer remain in its withdrawn position, but will be moved outward by the spring into a position such as shown in Fig. 15, where it lies alongside of the abrupt face 208 on the blade of the member 205.

It will also be clear that, if the cam H move the cam roller 175 far enough to bring the catch pin 178 into the position illustrated in 60 Fig. 15, then, as the cam face recedes, the pin 178 will move into contact with the abrupt face 208, the position illustrated in Fig. 16, and will be held there as long as the stop 205 blocks it. Indeed, in operation, this separation of the cam 65 roller 175 and the face of the cam H continues

during that period wherein the capper frame F is moved upward and downward in the capping operation. Consequently, the cam roller 175 is kept from vertically sliding over the face of the cam. In certain prior structures, the cam roller 5 was forced over the cam face while the two were in contact. The new construction avoids this.

Now the auxiliary cam member 200 comes into play to block the outward movement of the catch pin 178 at certain times in the operation of the 10 mechanism. During the first advance movements of the catch pin, however, the auxiliary stop 200 is not in position to block the downward movement of the catch pin 178. As clearly shown, the movement of the pin 178 over the inclined 15 face 207 is accompanied by the pin acting upon the auxiliary member 200 to tilt it in the manner illustrated in Fig. 15. This is brought about by the pin pressing against a pair of uprights 209 upon the member 200, which action causes the 20 member 200 to tilt about its pivot 210 against the pull of gravity upon the weighted end 211. The auxiliary stop 200 remains thus tilted until there has been a vertical movement of the capping frame F. When the latter takes place then 25 the rocker arm 164 and the parts connected with it are moved upwardly into the position illustrated in Fig. 17. This upward movement of these parts causes the pin 178 to clear the uprights 209, and thus allow the auxiliary stop to drop into blocking 30 position. In this blocking position, the upper face 212 of the member 200 lies directly beneath the pin 178.

Upon a downward movement of the frame F with its associated parts, following the position of 35 Fig. 17, the pin 178 will encounter the face 212 of the auxiliary stop and will be forced inward against its spring 180. Thus, the spring will be compressed and the pin 178 moved upward relative to the main stop 201. When the parts are 40 brought into their fully descended position, then the pin 178 will clear the upper end of the stop 201 and be free to slip over the same into a position in which it will be free of the stop but under the control of the cam. The cam is so shaped 45 that its face will approach the cam roller 175 very closely and be in readiness to receive it as soon as it is freed from the catch mechanism, so that there may be no hammer blow of the cam roller against the face of the cam. The point at which 50 the catch pin is about to slip over the main stop is illustrated in Fig. 18 and, as there shown, the cam face is near the cam roller. As clearly shown, the cam roller 175 is so near the cam face that the passing of the roller into engagement 55 with the cam face will be with little shock to the parts, and that shock will be taken up by the cushioning member 213. This member 213 is composed of rubber or other resilient material. A portion of the cam rim 121 is removed and a 60 space made for the member 213 which has its outer roller engaging face formed as a continuation of the metal face 121. Suitable pins 214 hold the cushion 213 in place. These pins pass through openings in the rubber block into tight 65 fitting engagement with the body of the cam 122. Heads on the pins 214 serve to hold the block 213 from slipping off the pins.

As soon as the catch pin has moved out of the control of the main stop of the catch mechanism 70 then the rocker arm will be wholly under the control of the cam face and the parts will occupy some such position as illustrated in Fig. 19.

The relation of the cam surface upon the cam H to the various actuating mechanisms G as the 75

carrier C and the head E are rotated is shown quite clearly in Fig. 3. In that view the mechanisms G rotate clock-wise as indicated by the associated arrow. For convenience in considering this relation, the six positions illustrated in Fig. 3 are designated *a*, *b*, *c*, *d*, *e* and *f*. In the same figure radial lines *x*, *y* and *z* indicate the points at which the compressed air is supplied to the bottle lifters D. The radial lines *x* and *y* indicate the range through which the low pressure air is applied. The radial lines *y* and *z* indicate the range through which the high air pressure is applied. The rest of the circle indicates the range through which the lifter pistons have their supply ducts connected to atmosphere. These radial lines *x*, *y* and *z*, if transferred to Fig. 4, would pass through the plugs 61, 68 and 69, respectively.

As the parts are shown in Fig. 3, the actuating mechanisms G occupy different positions. In this figure the last of the bottles received by the machine would be that upon the lifter D at the "*a*" position. This is true because the conveyer wheel 215 coacts with the fixed guide 216 to deliver incoming bottles to the lifters. In like manner the last bottle upon the machine would be that upon the lifter at the "*f*" position. When the bottle reaches this position the conveyer wheel 217 coacts with the guide 218 to deliver the bottle from the machine.

The conveyer for bringing the bottles to the machine and delivering the same therefrom may take any desired form. That disclosed in our prior Patent No. 1,992,693 will be satisfactory for the purpose. Only a portion of the conveyer is shown herein, that portion designated 219. It is the portion which receives the bottles after they leave the machine. A similar portion for conveying the bottles to the machine may be employed. When such is the case the guide 216 is associated with the incoming portion and the guide 218 is associated with the outgoing portion.

When we come to consider the various positions of the parts of the actuating mechanisms G in connection with the cam, all as shown in Fig. 3, we need to keep in mind the catch mechanism, the cap advancing blade and the application of air to shift the carrier frame to apply the caps. If we start with the position of a particular mechanism G at the time when the parts are in the "*d*" position and pass clock-wise around the cam we may follow the operations of the various parts of the mechanism without difficulty. At the time the parts are in the "*d*" position the cam roller 175 has just come into engagement with the cam face. This is a position which closely follows in time of operation, the position illustrated in Fig. 18. In the latter figure the cam roller has not yet contacted with the cam face. In position "*d*" the cam roller is shown in contact with the cam face. It will be noted that the cam has a protruding portion 222 on the right hand as the parts are viewed in Fig. 3, a somewhat similar protruding portion 223 on the left, an intermediate portion 224 of considerable length lying between the protruding portions 222 and 223 on the one side and finally a re-entrant portion 225 also between the protruding portions 222 and 223 but on the other side of the cam from the portion 224.

As soon as the cam roller 175 has come into engagement with the protruding portion 222 the arm 164 will be free of the catch mechanism and will be under the sole control of the cam face. In this position the catch mechanism members 200 and 201 occupy the positions shown in Fig. 18.

At this time the cap advancing blade 147 will be in its retracted position, namely, the position shown in dotted lines in Fig. 7. As before noted the stops 185 and 186 will be in engagement at this time.

As we pass from position "*d*" to position "*e*" the cam roller will travel over the receding portion of the cam face and will approach the greatest recession at the point 225. As the cam roller thus travels, the catch mechanism will remain as before and the blade 147 will gradually advance under spring action so as to carry a cap into the ram chamber. During all of this time the associated lifter D will be in its lowest position because its port 54 will be directly connected to atmosphere through the passage 75 (see Fig. 4).

In the present instance, in passing from position "*e*" to position "*f*", the cam roller 175 passes out of engagement with the cam face and at this time the blade 147 is in its most advanced position. This is the position illustrated in Fig. 5. At this time the lifter D remains down and the catch mechanism remains in its normal position.

In passing from position "*f*" to position "*a*" the cam roller 175 passes out of the re-entrant portion 225 of the cam and ascends the adjacent cam surface. As it ascends, it rocks the associated shaft 160 and gradually moves the blade 147 toward its withdrawn position. The movement between these positions, however, does not carry the blade backward the full extent but such further movement is left for subsequent treatment.

In passing from position "*a*" to position "*b*" the cam roller 175 approaches the protruding portion or hump 223 and in so doing continues the outward movement of the arm 164 and finally brings the blade 147 into its fully retracted position, that is to say, into the position illustrated in Fig. 7 wherein the stops 185 and 186 are in engagement. This engagement of the stops occurs a little before the cam roller reaches the high spot in the hump 223. When the latter position is reached then, as before pointed out, the second spring, namely, spring 181, is put under tension and the rocker arm 164 is advanced to 45 catch-engaging position. In other words, as the roller 175 passes up over the hump the catch-pin 178 rides over the inclined face 207 of the stop 205 in the manner indicated in Fig. 14. When the peak of the hump is reached by the cam roller then the parts are in the position indicated in Fig. 15, the catch pin 178 having passed over the inclined face 207 of the stop 205 and dropped down behind the abrupt face 208 of the stop. While the roller engages the peak, the pin 55 178 is held far enough away from the stop 205 to allow the pin to protrude under the action of its spring 180.

As soon as the cam 175 passes a little beyond the hump, that is to say, a little beyond the position illustrated in Fig. 15, then the cam face recedes and the rocker arm moves back under the action of its spring 181 until the pin 178 strikes the abrupt face of the stop 205, as indicated in Fig. 16. When this position of the parts is reached, the rocker arm is held against further return and the blade is held in its fully retracted position. From this point on, the cam roller 175 is no longer in engagement with the cam face but the latter gradually recedes from the former leaving the parts in some such position as illustrated in Fig. 16.

This traverse of the mechanism G is accompanied with a like travel of the associated lifter D. As before pointed out, the port 54 of this 75

lifter has been up to this point, in continuous communication with atmosphere. In traveling between positions "a" and "b" the connection of the port is changed as will be apparent from an inspection of the positions of the air connections in Fig. 4 and as indicated in Fig. 3 by the radial line "x". The passing from the atmospheric connection to the low pressure air connection causes the associated lifter D to rise. If there is a bottle on the lifter at this time, then the top of the bottle will engage the under side of the capper frame F and be in readiness for a further movement to apply the cap. The latter movement will occur when the particular mechanism passes into the range of the high pressure air between the radial lines "y" and "z". At this time the cap which was positioned beneath the ram in the manner shown by the cap 143 of Fig. 5 will be in readiness for application to the bottle and as soon as the high pressure air is applied the lifter will be forced upward and the bottle carried by it will move the capper frame F still further upward and the cap will be passed over the beveled surface 142 and through the throat 141 into its final position in the bottle. The ram 126 will apply pressure to the cap and bring about its proper positioning in the top of the bottle. All of this time, the arm 164 will be held in its extreme position by the catch mechanism and the capper blade will be fully retracted.

In passing from position "c" to position "d", the port 54 of the lifter D will be moved into registry with the atmospheric connection and thereupon the capper frame F will descend to its normal position. At the time this descent of the capper frame and its associated parts occurs, the cam roller 175 will still be out of engagement with the cam face. Thus, it will be seen that the raising and lowering of the cam roller 175 will occur while the same is clear of the cam face. As the parts approach the position "d", the cam face will approach the cam roller 175, and, finally, when the protruding portion 222 reaches the roller, the catch mechanism will free the latter and allow it to pass into the control of the cam, all as previously explained, and as clearly indicated by the positions of the parts in Fig. 18.

Thus, the cycle of travel has been completed and the parts are again ready to perform a like series of operations. It will be apparent that each of the mechanisms G will operate in this way and consequently it will be possible to cap six bottles during each revolution of the head E and its capping mechanisms. If for any reason one of the lifters D does not carry a bottle, then, obviously, the upward movement of the lifter by reason of the application of air under pressure will not force the associated capper frame upward, and, consequently, there will be no capping operation. Under such circumstances the rocker arm will remain in its outer position, being held by the catch mechanism until the same has made a complete revolution. It will then be in readiness to apply a cap to a new bottle should the same be properly presented. From these considerations of Figs. 3 and 4, we have seen how a bottle is placed upon a capper lifter and carried on through successive positions and finally delivered with a proper cap in its top, or held for subsequent service should a bottle be missing.

Obviously, the gear wheel 78 which drives the ring gear 76 located on the under side of the carrier C may be driven in any suitable way. In

the present instance the arrangement is like that disclosed in our prior Patent Number 1,992,693 and need not be restated. Similarly the machine will be provided with suitable legs and adjustable feet, one leg 220 and foot 221 only being shown. 5

In order to adapt the capper to bottles of different sizes, some adjusting means must be employed. In the present instance, we employ the adjusting mechanism K which is substantially the same as the adjusting mechanism for a like purpose employed in our prior Patent Number 1,992,693. It provides for the raising and lowering of the supporting head E and the parts which are carried by it. In brief, this is done by raising and lowering the center rod 38 which passes up through the tubular standard 43 upon which the various capper parts are mounted. The lower end of the rod 38 terminates in a threaded reduced portion 226 and this reduced portion passes through a horizontal web 227 of 20 an end member 228. Nuts 229 threaded upon the end 226 engage opposite sides of the web 227 to determine the adjustment between the rod 38 and the member 228. Besides being furnished with the web 227 the member 228 has an upper portion 230 which is provided with a central bore through which the lower end of the rod 38 passes. This structure strengthens the connection between the member 228 and the rod 38 and yet allows for a nice adjustment of the parts 30 relative to each other. The lower end of the member 228 has aligned bosses 231 which receive bearing pins 232 which are secured to the bosses by transverse set screws 233, the outer ends of the pins 232 being headed, in order to properly 35 hold previously positioned links 234. Thus, the links have a pivotal connection with the lower end of the member 228, one link being on one side and the other on the other side. In a similar manner, the upper ends of the links 234 are 40 connected to the bifurcated ends 235 of a crank arm 236, which is secured by suitable means to a shaft 237. Headed pins 238 provided with transverse holding pins 239 furnish the pivotal connection between the links 234 and the bifurcated arms 235, the shaft 237 is journaled in suitable supports such as hangers extending downward from the under side of the frame of the machine. One of these hangers, designated 45 240, is shown.

It will be apparent that by rocking the shaft 237 the central rod 38 may be moved up and down so as to adjust the head E and its associated mechanisms to bottles of different heights. As before pointed out, the head E is free to rotate relative to the rod 38 but must move up and down with it. The various parts by which the shaft 237 may be rotated are not given herein. They are substantially the same as disclosed in our prior Patent No. 1,992,693. 50 55

The ram or plunger comprises an upper portion 243 which has a diameter fitted to slide within the upper portion of the bore of the member 131 of the vertically adjustable capper frame F. It will be noted that the lower portion of the bore 65 in which the ram travels is of smaller diameter than the upper portion. Within the lower portion a cylindrical head 244 is adapted to travel. Between the portions 243 and 244 of the ram there is a reduced portion 245 around which is 70 coiled a compression spring 246. The latter bears at its upper end against a shoulder 247 formed on the under side of the portion 243 and at its lower end against a washer 248 which is fitted within the larger bore and adapted to rest upon a 75

- shoulder 249 formed at the point where the diameter of the bore is decreased. This construction is such that the spring 246 acts between the ram on the one hand and the frame member 131 on the other. When the frame is moved upward the spring 246 is compressed so as to allow a certain cushioning action when the bottles engage the frame member 232 and the cap is being applied.
- 10 In standardizing the ram structure the upper bore may be made the same for all machines. In such case the portion 243 of the ram would be likewise the same for all machines. The intermediate portion 245 and the projecting shank 250 formed integral with the rest of the ram may also be the same for all machines. The lower end of the shank 250 is preferably threaded at 251 to receive the head 244. The latter and the bore in which it travels may be made of different sizes to suit the size of the cap to be used. It is the cap size that governs. The head 244 is centrally apertured and threaded on its interior so as to be screwed upon the shank 250. The set screw 252 passing through a horizontal threaded opening in the head is adapted to engage a reduced portion of the shank 250 to hold the head in its proper position. The under side of the head 244 may be dished out to form a recess 253 and the periphery of the same near its lower end may be cut away as indicated at 254 so as to provide space which will prevent jamming of the cap as it is shoved upward against the plunger and carried on over the inclined face 142 and through the throat 141 into its final position in the top of the bottle.
- It will be clear that with this ram structure it is the head 244 which encounters the cap. Hence for caps of different sizes, heads of different diameters may be used, and then the lower end of the bore of the member 131 given a diameter to suit. Thus, to suit different orders, a minimum of work is required, the rest of the ram and frame being of the same construction for all machines.
- 45 It will be apparent that the machine will apply caps with tabs as well as caps without tabs. This has been mentioned in connection with the cap advancing blade 147 and the shape of its forward end. But it should also be noted that in the illustrations only disk caps are shown. These caps, forming the stack 139, are, as usual, placed in a container 220 and this container is turned bottom side up and passed down into the interior of the ovoid magazine chamber 138 to occupy the position shown in Figs. 5 and 6. The container 220, being intended for disk caps, is circular in cross section. If the container held tabbed caps then it would be more or less ovate in cross section to agree with the section of the magazine 60 138. In both cases the open end of the inserted carton or like container 220 stops short of the bottom of the magazine 138. Below this open end the inner walls of the magazine slope inward and downward to outlet openings 221 that are positioned and dimensioned so as to pass the tabs of double tabbed caps. The slope given the interior wall surfaces, indicated at 241 and 242, gives a sort of bell-mouthed entrance for the tabs and if any caps should be a little to one side, 70 off-center, so to speak, then they will, as they move downward, adjust themselves so that their tabs will be in alignment with the openings 221. Then when each tab reaches the bottom of the stack it will be properly engaged by the blade 75 147 and advanced as it should be. Obviously,

single tabbed caps, and a container for such caps, may be used if desired. In such event only one of the openings 221 and one pair of guiding walls 241 and 242 would come into play.

In the particular machine illustrated, provision is made for oiling the central standard by forcing lubricant into the central rod 38. For this purpose the rod 38 is tubular, having a central passage 255. At the lower end of the passage is a fitting 256 suited to receive the discharge nozzle of a grease gun. By means of the latter a suitable lubricant may be forced under pressure into the passage 255 and up through the same to its upper end. There two or more tubes 257 lead to points above the head 108 of the member 106, the one on the outside of a circular dam 258 and the other on the inside. The lubricant thus forced into the upper side of the head 108 will pass through the tubes 257 and on to the adjacent parts which require lubrication. That supply of lubricant which goes to the inside of the dam 258 passes to the members which are innermost in the column structure while that supply which goes to the outside will lubricate the outer bearing surfaces. The latter include the contacting surfaces between the sleeve member 106 and the sleeve portion of the cam member. A suitable annular groove 259 about the outside of the sleeve member 106 receives lubricant which passes down between the adjacent surfaces of the sleeves 106 and 115. From this annular groove, the lubricant passes through one or more openings 260 and supplies members inward of the sleeve member 106. Again, in the case of the bearing faces on the carrier head and the bearing number 55, which provide the main air valve faces, lubricant may be supplied through a pipe 264 on the under side of the member 55 and fed under pressure up through the passages 265 to the bearing faces and thus lubricate the latter. Obviously many forms of lubricating systems might be employed. What is here described is merely illustrative, and in itself forms no part of the present invention. The tubing at the top of the column of the machine is preferably protected by a cover 261 which fits at its lower edge about the hub of the cam member H and is apertured at its upper center to pass the upper threaded end of the rod 38. A plug 262 is threaded into the upper end of the rod 38 to close the bore thereof, the interior of the rod being threaded for the purpose. A cap nut 263 is threaded upon the outside of the protruding end of the rod 38 and bears down upon the cap 261 to hold it firmly in place.

It will be obvious from what has been said that in carrying out our invention still other forms may be employed than those set forth herein. It is therefore our aim to cover by the terms of the appended claims all those forms and alterations or modifications which rightly come within the spirit and scope of our invention.

We claim:

1. A bottle capping machine comprising a cap applying ram, means for rotating said ram about a vertical axis, a cap magazine, a cap advancing blade for removing caps from said magazine and presenting them seriatim to said ram, a vertically movable frame carried by said ram and movable thereon and in turn carrying said magazine and blade, a rock shaft journaled in said frame, said shaft being operative to actuate said blade to bring about said cap advances, a rocker arm secured to said shaft, a cam independent of said frame and operative during the travel of said ram about said vertical axis to actuate said arm 75

- to rock said shaft to and fro to actuate said blade, said cam having an extended face portion with less extended face portions adjacent thereto, said extended portion serving to engage said arm and move the same to an extreme position, spring means tending to move said arm toward said cam, and catch mechanism for seizing and holding said arm in said extreme position notwithstanding the withdrawal of the cam face from engagement with said arm as the parts continue their rotation, said catch mechanism responding to an up and down movement of said frame on said ram to free said arm for subsequent engagement with said cam.
- 15 2. A bottle capping machine comprising a rotary supporting head, a cap applying ram carried by said head, a cap magazine, a cap advancing blade for removing caps from said magazine and presenting them seriatim to said ram, a vertically movable frame carrying said magazine and blade, a rock shaft journaled in said frame, said shaft being operative to actuate said blade to bring about said cap advances, a rocker arm secured to said shaft, a stationary cam for actuating said arm to rock said shaft to and fro to actuate said blade as said head rotates, said cam having an extended face portion for engaging said rocker arm and less extended face portions adjacent thereto, said extended portion serving to move said arm to an extreme position, a main spring tending to move said arm toward said cam, a catch pin, a cooperating main catch stop, a second spring for yieldingly pressing said pin into position to engage said stop, said stop being beveled to allow said pin to pass the end of the stop and be held thereby in said extreme position, said arm being thus held by said pin and stop in said extreme position independently of further travel of said head, said frame being movable upward with said rocker arm held free from the less extended face portions of said cam, and means responsive to the subsequent downward movement of said frame to clear said pin from said stop thereby to free said arm for subsequent operation.
- 45 3. A bottle capping machine comprising a cap applying ram, a cap magazine, a cap advancing blade for removing caps from said magazine and presenting them seriatim to said ram, a vertically movable frame, a rock shaft journaled in said frame, said shaft being operative to actuate said blade to bring about said cap advances, a rocker arm secured to said shaft, a cam for actuating said rocker arm to rock said shaft to and fro to actuate said blade, said cam having an extended face portion for engaging said rocker arm and less extended face portions adjacent thereto, said extended portion serving to move said arm to an extreme position, a main spring tending to move said arm toward said cam, a catch pin, a cooperating main catch stop, a second spring for yieldingly pressing said pin into position to engage said stop, said stop being beveled to allow said pin to pass said stop to hold said arm in said extreme position after said extended face portions of the cam and said rocker arm are disengaged, and an auxiliary stop supported independently of said vertically movable frame, said auxiliary stop being movable into a set position in response to a movement of said arm and responsive subsequently to movements of said vertically movable frame to assume a freeing position in which it is operative to shift said pin to free said pin from said stop and thereby free said arm for subsequent operation under the influence of said main spring.
- 5 4. In a bottle capping machine, cap positioning and applying mechanism comprising a cap applying ram, a frame mounted for vertical movement on said ram, a cap advancing blade, a rock shaft carrying said blade, a spring retracted 5 rocker arm for actuating said rock shaft and blade, and a cam for moving said arm against the action of said spring to bring said arm to an extreme position, said cam being located a fixed distance above said ram, in combination with 10 catch mechanism for seizing and holding said arm in said extreme position out of the subsequent control of said cam during an upward movement of said frame, said catch mechanism comprising a spring pressed catch pin, a cooperating beveled stop operative to receive said pin upon its beveled face and under the said movement of said arm to compress the spring of said pin and allow said pin to slip into holding position against an abrupt face of said stop, and 15 means responsive to the subsequent downward movement of said frame to clear said pin from said stop thereby to place said arm again under the control of said cam.
- 20 5. In a bottle capping machine, cap positioning and applying mechanism comprising a vertically movable frame, a spring retracted rocker arm carried by said frame, and a cam for moving said arm against the action of said spring to bring said arm to an extreme position, in combination 25 with catch mechanism for seizing and holding said arm in said extreme position, said catch mechanism comprising a spring pressed catch pin, a cooperating beveled stop operative to receive said pin upon its beveled face and under the 30 said movement of said arm to compress the spring of said pin and allow said pin to slip into holding position against an abrupt face of said stop, and means responsive to the movements of said vertically movable frame to again compress the spring 35 of said pin and withdraw said beveled stop from engagement with said pin while the spring of the latter remains in compressed condition thereby to free said arm for further control by said cam.
- 40 6. In a bottle capping machine, cap positioning and applying mechanism comprising a vertically movable frame, a spring retracted rocker arm carried by said frame, and a cam for moving said arm against the action of said spring to bring said arm to an extreme position, in combination with 45 catch mechanism for seizing and holding said arm in said extreme position, said catch mechanism comprising a spring pressed catch pin, a cooperating beveled stop operative to receive said pin upon its beveled face and under the said 50 movement of said arm to compress the spring of said pin and allow said pin to slip into a latching position against an abrupt face of said stop, and an auxiliary stop supported independently of said vertically movable frame, said auxiliary stop being movable, first, into set position by the movement of said pin and stop into said latching position and, second, into catch freeing position by movements of said vertically movable frame to liberate said arm for subsequent operation under 55 the control of said cam.
- 65 7. In a bottle capping machine, cap positioning and applying mechanism comprising a vertically movable frame, a spring retracted rocker arm carried by said frame, and a cam for moving 70 said arm against the action of said spring to bring said arm to an extreme position, in combination with catch mechanism for seizing and holding said arm in said extreme position, said catch mechanism comprising a spring pressed 75

- catch pin on said arm, a cooperating beveled stop carried by said vertically movable frame and operative to receive said pin upon its beveled face and under the said movement of said arm
- 5 to compress the spring of said pin and allow said pin to slip into holding position against an abrupt face of said stop, a support independent of said vertically movable frame, and a weighted auxiliary stop pivoted to said support and having a
- 10 protruding end adapted to be engaged by said catch pin as the latter advances upon said beveled face, said engagement setting said stop member in abnormal position, said auxiliary stop being freed from said pin upon upward
- 15 movement of said vertically movable frame and rocker arm so as to drop back into normal stopping position beneath said pin, the pin being blocked by said protruding end as said frame and arm move downward and being held until said
- 20 beveled stop moves downward out of the return path of said arm, whereupon said arm is freed for subsequent operation under the control of said cam.
8. A bottle capping machine including a vertical ram, a capper frame mounted upon and movable to and fro lengthwise of said ram, a vertical rock shaft journaled in said frame, a cap magazine, a cap advancing blade secured to the lower end of said shaft, an actuating arm mounted on said shaft, forward and back stops for limiting respectively the forward and return movements of said shaft and blade, a first spring operative between said frame and shaft to advance said blade, a second spring operative between said arm and shaft to permit said arm to have a further return movement beyond that allowed by said back stop, said second spring being stronger than said first spring, catch mechanism for holding said arm in a position sufficiently retracted to place both of said springs in service, said catch mechanism being operative in response to movements of said frame to free said arm, and a cam mounted independently of said capper frame for actuating said arm when freed from said catch mechanism.
9. A bottle capping machine including a capper frame, a tabbed cap magazine carried by said frame, a ram chamber and a ram therein adjacent to said magazine, a channel formed in said frame of a size and location to pass caps from the bottom of a stack of caps in said mag-

azine to a cap applying position in line with said ram, and a cap advancing blade movable to and fro to advance said caps seriatim along said channel, as aforesaid, the forward end of said blade having two ledges for the lowermost cap to rest upon as the blade advances, also shoulders extending above said ledges for engaging the rear edge of the lowermost cap as it is being forwarded, the upper surface of the blade to the rear of said shoulders serving to support the cap stack in the magazine as the lowermost cap is being advanced away from said stack, also a recess below the level of said ledges and between them for a tab on the lowermost cap to enter as the cap is being forwarded, said recess being wide enough to readily embrace a cap tab and thereby allow said ledges and shoulders to properly act upon the cap edge on either side of the tab.

10. A bottle capping machine including a capper frame, a tabbed cap magazine carried by said frame, a ram chamber and a ram therein adjacent to said magazine, a channel formed in said frame of a size and location to pass caps from the bottom of a stack of caps in said magazine to a cap applying position in line with said ram, and a cap advancing blade movable to and fro to advance said caps seriatim along said channel as aforesaid, the forward end of said blade having two ledges for the lowermost cap to rest upon as the blade advances, also shoulders extending above said ledges for the rear edge of the lowermost cap to engage as it is being forwarded, the upper surface of the blade to the rear of said shoulders serving to support the cap stack in the magazine as the lowermost cap is being advanced away from said stack, also a recess below the level of said ledges and between them for receiving a tab on the lowermost cap as the cap is being forwarded, also an inclined surface at the forward end of said blade leading up to the forward edge of said recess, said recess being large enough to readily embrace a cap tab and thereby allow said ledges and shoulders to properly act upon the cap edge on either side of the tab and the inclined surface at the forward end of the blade serving especially to guide a cap having wire staples at its tab roots.
